UNITED STATES PATENT OFFICE.

CHARLES E. LINEBARGER, OF CHICAGO, ILLINOIS.

HUMIDIFIER.

Application filed October 6, 1920. Serial No. 415,214.

To all whom it may concern:

Be it known that I, CHARLES E. LINEBARGER, a citizen of the United States, residing at Chicago, in the county of Cook and State of Illinois, have invented certain new and useful Improvements in Humidifiers, of which the following is a specification.

This invention relates to humidifiers or to devices for mixing substances that are normally in the liquid state with substances that are normally in the gaseous state, as, for example, water and air or gasoline and air. Among the objects of my invention are to provide an improved device of the character indicated that is simple in construction and manufacture, efficient in operation and applicable to a number of different uses. While it is primarily intended to effect the mixture of water vapor and air, it may also be employed for the separation of dust from a gas and also for the mixing of gases other than air with vapors other than that of water. The invention has for one object the production of suitable humidifying apparatus which may be attached to ordinary fans for circulating the air, and particularly to small portable fans which are used in residences and offices. The general purpose of the apparatus is to provide means for effectively introducing into the air in cold weather a very material amount of moisture so as to raise the humidity of the air to any desired amount, and also to thoroughly cleanse the air of dust, smoke or other objectionable substances, and in warm weather to cool the air by the evaporation of water while the air is being cleaned and circulated. Other objects of the invention will be apparent from a consideration of the accompanying drawings and the following description thereof.

Of the drawings Fig. 1 is an elevation of an electric fan with apparatus attached thereto which embodies the features of my invention; Fig. 2 is an enlarged sectional view of a portion of the apparatus; Fig. 3 is a transverse section along the line 3—3 of Fig. 2; and Figs. 4, 5, and 6 are reduced transverse sections of apparatus showing modifications which may be made if desired.

The apparatus may be attached to any ordinary circulating fan in any suitable manner. I prefer to attach it to the ordinary guard of the fan, as indicated in Fig. 1. The apparatus comprises in general a casing which may be a tube 10 through

which air, by means of a fan 11, is blown longitudinally. The tube 10 may extend perpendicularly to the plane of the fan, or obliquely, as may be desired. I prefer to extend it perpendicularly to the plane as indicated. Within the tube is provided a shallow tank 12, the bottom of the tube providing a bottom for the tank, and end walls 13 for the tank being fixed in the tube in any suitable manner. The tank is supplied with water in any suitable manner, and any suitable means may be provided to maintain therein a suitable supply of water. I have illustrated for the purpose of this description an inlet pipe 14 which is supplied with a valve 15, and is connected with any suitable source of water supply under pressure. By means of the valve the amount of water flowing into the tank may be regulated, and the water may be shut off entirely when desired. I show also an overflow pipe 16 which extends upwardly into the tank to the point where it is desired to maintain the water level therein. Projecting from the hub 17 of the fan is a shaft 18 which passes into the tube 10 and has on its outer end any suitable apparatus for stirring up the water in the tank. I prefer for the purpose a stirrer consisting of the paddle 20. As the fan rotates the paddle throws a continuous current of water upwardly and around the sides of the tube; and the water then drips down from the walls of the tube, so that the air being forced through the tube is continuously passing through the spray of water going upwardly from the fan and downwardly from the walls of the tube, or from other devices which may be placed in the tube to assist in suitably distributing the water as it falls through the tube. I prefer for such a device a curved sheet 21, with its upper edge supported in any suitable manner and the suspended portion gradually curving inwardly towards the central portion of the tube, so that the water being forced upwardly by the stirrer passes between the sheet 21 and wall of the tube and is sprayed out through the openings 22 in the upper portion of the sheet, the speed of the water being increased by the decreasing cross-section of the space through which it travels upwardly. To prevent drops of water passing out of the tube in either direction baffle plates 23 and 24 of any suitable shape may be provided in the tube. With this arrangement, as the fan

2

operates, the current of air passing out of the tube will carry with it a very material amount of moisture, the amount depending upon the magnitudes and the relative adjustments of the various parts, so that the humidity of the air may be increased thereby as much as is desired. At the same time the air, being circulated continuously, will all be passed through the tube repeatedly and 10 will be thoroughly washed by the spray of water through which it passes. And also much of the air will be forced down into and through the water by the paddle 20. By these means the air and water will be 15 thoroughly churned together throughout the entire casing.

If it is desired, in order to pass more moisture into the air by increasing the temperature thereof, any suitable means may 20 be used for heating the water either before it passes into the tank or afterwards. I prefer for the purpose an electric heater 26 immersed in the water of the tank and connected to any suitable source of electric supply by means of cables 27.

The tube in this instance is shown as connected to the fan guard 30 by means of rods 31 fixed to the guard and also fixed to a band 32 passing around the tube. The band 30 is clamped around the tube by means of lugs 33 fixed to the end of the band and a suitable screw 34 so arranged that as the screw is loosened the tube may be conveniently slipped from the band. Also fixed to 35 the band is a conical shaped air interceptor 35 having a tubular outer end 36 surrounding the tube 10 under the band 32, slots 29 allowing it to be clamped to the tube by the band 32. This air interceptor extends 40 substantially to the guard of the fan and intercepts as much of the current of air from the fan as its construction provides for, so as to increase materially the flow of air through the tube 10. The tube 10 may 45 extend inwardly towards the fan so far as may be desired. I prefer to have it push inwardly against the guard and then be clamped in place. When so arranged the air passing through comprises that which 50 is forced through by the central portion of the fan opposite the end of the tube and also such an additional amount as is forced inwardly by the interceptor and thus forced through the tube. By this arrangement I 55 am able to vary materially the flow of air through the tube by suitable means such as the following:

In the wall of the interceptor 35 I provide openings 36; and, encircling the air 60 interceptor, I provide a conical shutter 37 shaped similarly to the interceptor and entirely enclosing it. This shutter, however, is rotatably mounted on the interceptor, held in place by the screw 39, and it has openings 38 corresponding to the openings 36

of the interceptor; so that when the respective openings register the air can pass freely therethrough and substantially no air is forced by the interceptor through the inner tube, the air external of this tube passing either through the openings or around the outer edges of the interceptor. But when the shutter is rotated so as to close more or less the openings 36 more or less air will be forced through the tube 10 by 70 the interceptor, and a very material amount will be forced through the tube when the openings are entirely closed by the shutter. To operate the shutter I provide an arm 40 fixed to the shutter; and any suitable 75 hygrometric device may be used for controlling the shutter in accordance with the humidity of the air. For this purpose I prefer a device 41 which consists of curved strips of metal and wood, or other suitable 80 materials, having one end 42 fixed to the band 32 by means of an arm 43, and the other end of the device 44 is fixed to the shutter by means of the arm 40, so that, as the air becomes moister and the inner 85 strip of wood straightens the hygrometric device, the shutter will be rotated on the air interceptor so as to open more the openings of the interceptor and decrease the amount of air flowing through the tube 10.

To further assist in decreasing the amount of air flowing through the tube a damper 46 may be provided in the tube itself and this may be suitably connected with the hygrometric device by means of an arm 100 47, a lever 48 and suitable connecting links. With the damper so arranged, as the device 41 operates to increase the openings through the interceptor, it also rotates the damper 46 to close more or less the bore of the tube 105 10. With these arrangements, if the air becomes too moist the humidifying effect of the apparatus may be substantially eliminated.

It will be understood that as the apparatus 110 operates, the dirt from the air will be carried into the tank continuously by the falling spray and it will be necessary at times to clean the tank and other portions of the apparatus. To provide for this I arrange for slipping the tube 10 out of the clamping band 32 by loosening the screw 34, and disconnecting the arm 47 from the lever 48 by means of a thumb screw 50; it being understood that flexible tubes 51 may be 115 used for supplying water to the tank, and also that, when the blade 20 is turned horizontally, it will pass freely between the end wall 13 of the tank and the baffle plates 23. I also provide means for removing the baffle 120 plates and the plate 21 from the tube by mounting these upon a curved plate or frame work 52, which may be readily slipped from the tube 10 when it is removed from its support. In this way the plates within 125 130

the tube may be easily cleaned and any dirt may be removed from the tank whenever occasion arises.

Although I have described with some particularity the various elements which comprise the apparatus, and their relative arrangements, yet it is to be understood that modifications may be made by those skilled in the art without departing from the spirit 10 of my invention as disclosed by the following claims. For example, Fig. 4 illustrates rotatable fins 55, against which water is thrown by the paddle 20 with such energy that the fins are rotated and they throw the 15 water off in a finer spray downwardly and along the walls of the tube. Fig. 5 shows a baffle 56 against which the water is forced by the paddle 20 and this assists in atomizing the water. Fig. 6 illustrates a squirrel 20 cage wheel 57, fixed to the shaft 18, and having longitudinal peripheral paddles 58, which not only throw the water upwardly from the tank but carry it upwardly by its adhesion and throws it outwardly by centrifugal 25 force, so as to very thoroughly atomize the water. Various other devices for the same purpose may be used.

I claim as my invention:

1. A humidifier comprising a casing of curved cross-section and partly closed at both ends, means for forcing a gas through said casing, means for maintaining a supply of liquid within said casing, a stirrer rotatably mounted within said casing and normally partially immersed in said liquid, means for rotating said stirrer so that said liquid is driven up around the inner wall of said casing, means for breaking up the current of liquid thereby produced, and means 40 for heating the water in said casing.
2. An air washer comprising a hollow casing with its ends open, a water tank

formed in the bottom of said casing, a paddle rotatably mounted in said casing and projecting into said tank, automatic means 45 for rotating said paddle, means for forcing a gas through said casing and means for regulating the amount of air being forced through said casing.

3. A humidifier comprising a fan, a hollow casing with its ends open mounted in front of and with one end towards said fan, a water tank formed in the bottom of said casing, a paddle fixed to the hub of said fan and projecting into said tank, means for rotating said fan, and means for heating said water.

4. A humidifier comprising a fan, a hollow casing with its ends open mounted in front of and with one end towards said fan, a water tank formed in the bottom of said casing, a paddle fixed to the hub of said fan and projecting into said tank, means for rotating said fan, and baffle plates in the end 65 of said casing.

5. A humidifier comprising a fan, a hollow casing with its ends open mounted in front of and with one end towards said fan, a water tank formed in the bottom of said casing, a paddle fixed to the hub of said fan 70 and projecting into said tank, means for rotating said fan, and automatic means for regulating the amount of air being forced through said casing by said fan.

6. A humidifier comprising a tube, the lower portion of the ends of said tube being closed to form a tank, a paddle rotatably mounted in said tank, means for forcing air through said tube and for rotating said paddle, and hygrometric means for varying the 80 amount of air forced through said tube.

In testimony whereof, I hereunto set my hand.

CHARLES E. LINEBARGER
